(57) **CLAIM**

The ornamental design for a vehicle wheel, as shown and described.

DESCRIPTION

FIG. 1 is a front plan view of a vehicle wheel embodying our new design.

FIG. 2 is a front perspective view thereof.

FIG. 3 is a rear plan view thereof.

FIG. 4 is a rear perspective view thereof; and,

FIG. 5 is a side view thereof.

The remaining side, top and bottom views are identical to FIG. 5.
